[57] CLAIM

An ornamental design for a equatorial region of a sundial, as shown and described.

DESCRIPTION

FIG. 1 is a front view of an equatorial region of a sundial showing my new design;

FIG. 2 is a left side elevational view thereof, the right side being a mirror image; and,

FIG. 3 is an enlarged front view thereof.

The broken line showing of FIGS. 1 and 2 are environmental only and form no part of the claimed design.

FIG.1

FIG.2

FIG.3
